METHOD OF MAKING CUTTING TOOLS

Otis C. Martin, Los Angeles, Calif.

Original application April 20, 1940, Serial No. 330,752. Divided and this application March 16, 1942, Serial No. 434,812

3 Claims. (Cl. 76—108)

My invention relates to a method of making boring and forming tools and has particular reference to a method of making a boring tool which is particularly adapted to the manufacture of fluid control valve bodies.

This application is a division of my copending application Serial No. 330,752, filed April 20, 1940, and entitled Method and apparatus for manufacturing valve bodies.

In my copending application Serial No. 323,376, filed March 11, 1940, entitled "Valve," I have described and claimed a novel fluid valve construction which is particularly adapted for use in aircraft for controlling various types of fluid power apparatus. The particularly notable advantages inherent in this new valve reside in its small size, light weight, and inexpensive construction. The present invention is directed to certain tools by means of which this new valve may be readily and inexpensively constructed.

Valves of the character disclosed in my aforementioned copending application Serial No. 323,376 employ a plurality of bores and chambers, a part of which are used to house valve members and a part of which constitute fluid entrance and exit openings. These bores and chambers are provided with various enlargements which function as fluid passages, and certain of these are disposed in intersecting relation with enlargements of adjacent bores to provide a fluid intercommunication between bores. Prior to my invention these bores and enlargements had to be formed by destructible cores employed in connection with the casting of cast valve bodies or, in the case of valves requiring a valve body of greater strength and higher quality than could be obtained by casting, by means of boring tools requiring the use of a separate tool for each bore and enlargement thereof and frequently required a separate and distinct "set up" of the boring machine for each operation. Such methods of manufacture are expensive and time consuming.

It is therefore an object of my invention to provide a method of manufacturing a boring tool which is particularly adapted to use in the manufacture of valves of the character set forth hereinbefore.

It is also an object of my invention to provide a method of making a boring tool comprising a tool shank and a laterally extending cutting element whereby the cross sectional shape of the shank is so proportioned with respect to the diameter of the bore enlargement to be formed by the tool as to provide a maximum possible amount of material in the shank.

It is another object of my invention to provide a method of the character set forth in the pre-

ceding paragraph of making a tool whereby there is imparted to the shank portion of the tool a lenticular cross section.

It is an additional object of my invention to provide a method of the character set forth in the preceding paragraph of manufacturing a tool whereby there is imparted to the shank portion of the tool a lenticular cross sectional shape defined by eccentrically disposed cylindrical surfaces, each having a radius of curvature substantially equal to the radius of the pilot bore in which the tool is to be used.

Other objects and advantages of my invention will be apparent from a study of the following specifications, read in connection with the accompanying drawing, wherein:

Fig. 1 is a fragmentary sectional view illustrating the manner in which a boring tool constructed in accordance with the method of my invention may be employed for providing enlargements in the pilot bores formed in a valve body;

Fig. 2 is a cross sectional view illustrating the manner in which tools of the character shown in Fig. 1 are received in their respective bores prior to the commencement of a boring operation;

Fig. 3 is a view similar to Fig. 2 but illustrating the position of the tools at the conclusion of the boring operation; and

Fig. 4 is a cross sectional view of the shank of a boring tool constructed in accordance with the method of my invention and illustrating the location of the principal axes employed in the forming operation whereby the particular shape illustrated in the drawing is imparted to the tool.

I have illustrated in the accompanying drawing the use of the tool of my invention as directed to the forming of a valve body of the character used in a valve such as that disclosed and claimed in my copending application Serial No. 323,376, filed March 11, 1940, entitled "Valve." The valve which is disclosed in that application employs a valve body 1 (see Fig. 1) within which is provided a discharge port 3 and a valve chamber bore 5. The discharge bore 3 is provided at its lower end with an enlargement 7 which intersects a similarly disposed enlargement 8 formed in the valve chamber bore 5.

The enlargements 7 and 8 which are to be formed at the lower ends of the bores 3 and 5 may be conveniently bored by means of a boring tool such as that illustrated in the drawing. This tool preferably comprises a bar portion 14 adapted to be carried in the tool carriage of a suitable boring machine or engine lathe. The bar 14 bears on its outermost end a shank portion 15 which terminates in a cutter portion 16.

The block 1 is mounted for rotation about the

axis of the bore to be enlarged (such as the bore 3 in Fig. 1) as by clamping the block 1 securely to the face plate or in a chuck of an engine lathe. The bar portion 14 is suitably mounted on the tool carriage of the lathe and the carriage is moved to such position as to insert the tool within the bore 3 to the desired depth. The block 1 is then rotated and the tool is moved laterally relative to the axis of rotation of the block 1 so as to bring the cutter portion 16 thereof into engagement with the walls of the bore and remove the material therefrom to provide the enlargement 8.

According to the preferred embodiment of my invention, the cutter portion 16 and the shank portion 15 are formed integrally with each other and integrally with the bar portion 14 as illustrated in Fig. 1. In accordance with the preferred method of manufacturing the tool, a bar portion 14 of any desired size is first turned as by means of a lathe to a cylinder having a diameter slightly smaller than the diameter of the bore 3 or 5 in which the tool is to be used, as is indicated by the dotted line 17 in Fig. 4, and having a length somewhat in excess of the depth of the bore 3 or 5. This cylindrical portion may be formed in a lathe by rotating the bar 14 about its longitudinal axis indicated by reference character 18 in Fig. 4. The shank portion 15 is then formed by cutting away the material from one side of the cylindrical portion 17. This may be done by mounting the cylinder 17 for rotation in a lathe about an axis such as that indicated at 19 in Fig. 4 and cutting the material by means of a lathe tool along a surface 20 which is concentrically disposed relative to the axis 19 and which has a radius of curvature equal to the radius of the cylindrical portion 17.

Since it is desired to retain a maximum amount of material to serve as the shank portion 15 in order that the strength thereof may be maintained at a maximum, the offset between the axes 18 and 19 is so adjusted as to permit the surface 20 to be brought into contact with the sides of the bore 3 or 5 at the time the tip of the cutter 16 has reached its maximum lateral penetration to form the enlargement 7 or 8. The offset between the axes 18 and 19 will be found to be equal to one-half the difference in diameter between the bore in which the tool is to be inserted and the diameter of the enlargement to be cut therein. For example, if it is desired to cut a one inch diameter enlargement in a $\frac{5}{8}$ inch diameter bore, the offset between the axes 18 and 19 will be $\frac{1}{16}$ of an inch or one-half of $\frac{1}{8}$ inch, the difference between one inch and $\frac{5}{8}$ of an inch.

I have indicated by means of a dotted circle 21 in Fig. 4 the maximum permissible diameter which could be employed on the shank 15 if that shank were formed of cylindrical cross section. It will be observed that a substantial increase in the amount of material retained in the shank 15 is achieved by forming the shank with a lenticular cross section as above described, and attention is further directed to the fact that the long axis of this cross section is extended in the direction to best withstand the forces imposed thereon by the engagement of the cutter 16 with the block 1. After the shank 15 is formed, the upper part of the circular member remaining at the outermost end thereof is cut away along a line 21a to provide an upper tool race having the proper rake to give whatever cutting angle is desired at the cutting edge 21b of the cutter portion 16. Similarly, the underside of the cut-

ter portion 16 is preferably relieved along a surface 21c to provide for the required clearance between the flank of the tool and the work.

I have illustrated in Fig. 2 the relation of the cutter 16 and the shank 15 with the bore 3 or 5 at the time the cutter is inserted in the bore preparatory to cutting the enlargement 7 or 8. I have also illustrated in Fig. 3 the relationship between these parts at the time the cutting of the recess 7 or 8 is completed.

It will be apparent from the foregoing that I have provided a novel boring tool and method of making the same which provides a maximum amount of material in the shank portion of the tool interconnecting the cutter with the supporting bar portion and that this shank material is disposed in such configuration as to achieve the maximum strength and rigidity.

While I have in the foregoing described as a use to which the tool of my invention is particularly adapted, the manufacture of a particular type of valve such as that disclosed in my aforementioned copending application, it will be readily apparent to those skilled in the art that the tool is also well adapted to the manufacture of valve bodies of various types and in fact to the forming of bores having enlargements and recesses in metal parts of various descriptions.

While I have shown and described the preferred embodiment of my invention, I do not desire to be limited to any of the details of construction shown or described herein, except as defined in the appended claims.

I claim:

1. The method of making a boring tool for cutting in a valve body an enlargement of a pilot bore provided therein which consists in turning on an end portion of a piece of tool stock a cylindrical section having a diameter substantially equal to the diameter of said pilot bore, forming a tool shank portion of lenticular cross section by rotating said cylindrical section about an axis disposed parallel to the axis of said cylindrical section and spaced therefrom a distance substantially equal to the difference between the radii of said pilot bore and said enlargement and cutting a partially cylindrical surface thereon spaced from the end thereof and having a radius of curvature substantially equal to the radius of said pilot bore, and then cutting away the upper part of the end portion remaining to form an upper tool face intersecting said cylindrical section to define a cutting edge.

2. The method of forming a shank on a boring tool intended for cutting an enlargement in a pilot bore which consists in cutting away a stock member along partially cylindrical surfaces each having a radius of curvature substantially equal to the radius of said pilot bore and having axes spaced apart a distance substantially equal to the difference between the radii of said pilot bore and said enlargement.

3. The method of forming a shank on a boring tool intended for cutting an enlargement in a pilot bore which consists in successively rotating a stock member about parallelly disposed axes spaced apart a distance substantially equal to the difference between the radii of said pilot bore and said enlargement, and in each instance cutting away a part of said stock member by moving a cutting tool along a path parallel to said axis and spaced therefrom a distance substantially equal to the radius of said pilot bore.
